UNITED STATES PATENT OFFICE.

JOHN W. DUNLAP, OF CHICAGO, ILLINOIS, ASSIGNOR OF ONE-HALF TO CLARENCE C. TRAVIS, OF CHICAGO, ILLINOIS.

TYPE-WRITER.

1,009,391

Specification of Letters Patent. Patented Nov. 21, 1911.

Application filed July 21, 1909. Serial No. 508,817.

To all whom it may concern:

Be it known that I, JOHN W. DUNLAP, a citizen of the United States, residing at Chicago, in the county of Cook and State of Illinois, have invented certain new and useful Improvements in Type-Writers, of which the following is a specification.

This invention relates to type-writing machines in general, but is more especially related to book typewriters.

The primary object of this invention is to provide an improved construction and arrangement of parts in the feed mechanism of typewriters.

Other and further objects will appear in the following specification and be more particularly pointed out in the appended claims, for which purpose reference may be had to the accompanying drawings showing an exemplification of this invention.

In the drawings—Figure 1 is a plan view of a book-typewriter embodying my invention. Fig. 2 is a side elevation of the same. Fig. 3 is a detail side elevation of the carriage. Fig. 4 is a detail of a portion of the type-bar operating mechanism. Fig. 5 shows the detail of the type-bar in one printing position. Fig. 6 shows the same in another printing position. Fig. 7 is a detail showing the means of operating the escapement mechanism. Fig. 8 is a perspective view of a portion of the type-bar frame. Fig. 9 is a detail of a portion of the escapement mechanism.

Referring more particularly to the drawings, the bed frame support of the type-writing machine may be of any suitable construction, that shown in the drawings comprising platen 1 surmounted by a track 2 comprising sections 2 and 3, the section 3 of said track being pivotally connected at 4 with the section 2. Said track is provided above with a rack 5 with which meshes the gear wheels 6, 6, and 7, 7, by which a carriage 8 is movably mounted in such manner as to adapt it to be passed up and down the platen at will. This traveling carriage 8 comprising the end frames 9, 10 is provided above with guide-rods 11 and 12, upon which is slidably mounted a type-bar frame 13, of any suitable construction for mounting the type-bar mechanism to be hereinafter described and pointed out

in the claims. Preferably, however, this type-bar frame is made substantially rectangular, as shown in the drawings, and provided with forwardly extending arms 14, 15, which slidably engage the guide-rod 12, said frame being supported in front by means of bearings provided in the ends 55 of said frame which slidably engage the rod 11. The type-bar mechanism may be supported upon the frame 13 in any suitable manner, but according to the preferred means, as exemplified in the drawings, such 60 support comprises the arcuate racks or frames 16, 17 rigidly connected together by means of angular end supports one of which, 33, is clearly shown in Fig. 8, said end supports being provided with rigid projections 35, 36, slidably engaging in the slots 37, 38 within each end of the type-bar frame 13. By this means the type-bar mechanism is adapted to be shifted upwardly and rearwardly in the type-bar frame. 70 Slidably engaging the lower pin or projection 36 is a shift lever 39, which is pivoted intermediately of its ends at 40, and provided at one end with a slot 41 by means of which it slidably engages said pin 36. 75 The racks are provided with radially disposed slots 18, 19, which radiate from the printing point. Within the slots 18 of the arcuate support 16 are oscillatably pivoted a plurality of type bars 20, each of said type 80 bars comprising a shank portion and an integral head 21 angularly disposed relatively thereto. The head 21 is provided with facets 22 and 23 whereon may be mounted the usual upper and lower case characters. 85 The inner end of type-bar 20 is pivotally mounted within one of the slots 18 in the arcuate bar 16, and is provided with a pinion concentric with its pivot and rigid therewith, said pinion in the preferred embodiment exemplified, consisting of an integral portion of said bar having gear teeth provided in the periphery of a portion extending concentrically around the pivot.

As contemplated by the present invention, the type-bar operating mechanism comprises any suitable key mechanism, which directly engages the type-bars, said key mechanism according to the exemplification shown on the drawings consisting 100 of a plurality of key levers 26 which are

preferably pivoted respectively intermediate of their ends within the slots 19 of the arcuate rack 17. Upon the outer end of each of said key levers is rigidly mounted the usual finger pad 27, while on the inner end suitable means for operably engaging the toothed end 28 of the type-bar 20 is provided. In the present embodiment this means consists of an arcuate rack 29 forming an integral portion of the key lever 26. As shown in Fig. 4 of the drawings, the key lever 26 is maintained normally raised by means of a resilient member or spring 30 secured at one end to a rigid portion of the type-bar frame, and at the other end to the arcuate rack end of said key lever 26. The normal position of the key levers is thus that position shown in Fig. 4, and in full lines in Figs. 2 and 3.

20 In order to provide suitable means of improved construction for effecting a direct connection between the key bar and the spacing mechanism, each of said key bars 20 is provided adjacently to its pivoted ends 25 with an integral lug 32. Swingly mounted in the type-bar frame 13 is a universal spacing bar 42, which may be of any suitable construction, but according to the preferred embodiment shown in the 30 drawings, is made arcuate in form to conform to the inner arcuate rack 16 within which the type-bars are pivotally mounted. Said spacing lever is by this means adapted to be impinged directly by the lug 32 of 35 each type-bar 20 when said type-bar descends into printing position. It will thus be seen that the spacing lever is actuated by direct impingement of the type-bar. Slidably engaging the spacing lever below is a 40 roller 43, or other friction-reducing device mounted on the extremity of an escapement lever arm 44, which is rigidly secured at one end to a pintle 47 carrying a shorter lever arm 47a upon which in turn are mounted 45 dogs 45, 46 of well known construction, seen best in Figs. 7 and 9 of the drawings. The dogs 45, 46 are moved into and out of engagement with a rack 48 rigid on the carriage 8 by the movement of the escapement 50 lever 44.

The operation of the type-bar mechanism will now be evident. Assuming the parts to be in the normal position shown in full lines in Fig. 2, whenever the key lever 26 is depressed into the position shown in dotted lines in Fig. 2, the type-bar 20 is moved into the position shown by dotted lines in the same figure, in which position the type character 25 is brought into printing position, the other type character 24, by reason of its relative angular disposition with reference to the character 25 being maintained out of contact with the paper or platen. As the type-bar 20 is being moved into the position shown in dotted

lines, it will be seen that the lug 32 will impinge directly upon the spacing bar 42, whereupon said spacing bar oscillates the escapement lever 44 to move the movable dog 45 in a well known manner out of engagement with the rack 48, whereupon the movable dog 45, under the action of the spring 49, moves end-wise approximately the distance of one tooth in the rack, so that as the type-bar 20 is raised by the action of 75 spring 30 upon the key lever 26, the rigid dog 46 is moved out of engagement with one rack tooth while the movable dog is moved into engagement with the next rack tooth, thus permitting the escapement of 80 one tooth of the rack. In order to bring the printing character 24 into printing position, as shown in Fig. 6 of the drawings, the shift lever 39 is depressed, whereupon the type-bar rack 16 is raised in such manner 85 as to cause the type-bar 20 to swing about its center at a different distance above the platen when the key lever 26 is depressed. It will thus be seen that the type-bar 20 is oscillatable about a moving center by means 90 of the pivoted lever 26 which enters into direct engagement therewith.

Mounted upon the lower portion of the carriage 8 is a ribbon shifting device 50, which may be operated in any suitable manner to move the ribbon into and out of printing position. Inasmuch, however, as this mechanism has no particular bearing upon the present invention, a detailed description thereof is not included in this 100 specification. In like manner, the detailed construction of the platen, including the means for holding the printed surface does not form any part of the present invention, and has not, therefore, been described in 105 detail.

What I claim is:

1. In a book typewriter, the combination with a pintle, of lever arms of unequal length mounted on said pintle, a feed dog 110 mounted on the shorter lever arm, a universal bar movably engaging the extremities of the longer lever arm, and a type bar adapted to impinge said universal bar.
2. In a typewriter, the combination with a universal bar and a plurality of type bars arranged to impinge upon said universal bar when they are actuated, a pintle, a lever mounted on said pintle below said universal bar, a roller on one end of said lever in 120 rolling contact with said universal bar, and a feed dog carried by said pintle.
3. In a book typewriter, the combination with a feed escapement mechanism comprising a pivotally mounted feed dog, an escapement lever rigidly connected to said dog and of relative great length compared to the distance of said dog from its axis of oscillation, said lever being provided 125 with friction reducing means on the outer 130

swinging end thereof, a universal lever operatively engaging said means, and a type-bar impinging said universal lever.

4. In a book typewriter, the combination
5 with a feed escapement mechanism comprising pivotally mounted feed dogs, a lever connected to and oscillatable with said feed dogs, said lever being of relative great length in comparison to the distance of the
10 feed dogs from the axis of oscillation, a pivotally mounted universal lever movably

engaging said oscillating lever, and a type-bar adapted to impinge directly upon said universal lever.

In testimony whereof I have signed my 15 name to this specification, in the presence of two subscribing witnesses, on this 15th day of July A. D. 1909.

JOHN W. DUNLAP.
